UNITED STATES PATENT OFFICE

164,320

THEATER FRONT

Victor A. Rigaumont, Pittsburgh, Pa.

Application August 27, 1949, Serial No. 4,873

Term of patent 14 years

(Cl. D13—1)

To all whom it may concern:

Be it known that I, Victor A. Rigaumont, a citizen of the United States, residing at Pittsburgh, in the county of Allegheny and Commonwealth of Pennsylvania, have invented a new, original, and ornamental Design for Theatre Front, of which the following is a specification, reference being had to the accompanying drawing forming part thereof.

In the drawing:

The dominant features of my new design are shown in solid lines in Figure 1.

I claim:

The ornamental design for a theatre front, substantially as shown and described.

VICTOR A. RIGAUMONT.
